UNITED STATES PATENT OFFICE.

DONALD J. CAMPBELL, OF MUSKEGON, MICHIGAN.

RING-TESTING MACHINE.

1,032,465.

Specification of Letters Patent. Patented July 16, 1912.

Application filed March 7, 1912. Serial No. 682,305.

To all whom it may concern:

Be it known that I, DONALD J. CAMPBELL, a citizen of the United States of America, residing at Muskegon, in the county of Muskegon and State of Michigan, have invented certain new and useful Improvements in Ring-Testing Machines; and I do hereby declare the following to be a full, clear, and exact description of the invention, such as will enable others skilled in the art to which it appertains to make and use the same.

My invention relates to improvements in ring testing machines and more particularly to such machines as shown in my co-pending application, Serial No. 653,856, filed Oct. 10th, 1911.

The object of my present invention is to provide the device with improved means for testing the rings by a torsional stress thereon and also to provide the scale beam and index with means whereby the amount of the ring removed to permit contraction and expansion of the same without permanent change of form or "set," may be indicated and to provide the device with various other new and useful features hereinafter more fully described and particularly pointed out in the claims, reference being had to the accompanying drawings, in which:

Figure 1 is a side elevation of a device embodying my invention; Fig. 2 a plan view of the same; Fig. 3 an enlarged detail in vertical section of the joint to permit the upper jaw to swing horizontally; Fig. 4 an enlarged vertical section on the line 4—4 of Fig. 1; and Fig. 5 a detail of the support for the vertical scale.

Like numbers refer to like parts in all of the figures.

1 represents the base of the machine on which the various parts are supported; 2 the lower jaw of the device being substantially semi-circular having two oppositely projecting upwardly curved arms forming the stationary or lower jaw of the device fixed on the base. 3 the upper jaw of the same these jaws being pivotally connected at one side to permit the upper jaw to swing 50 in a vertical plane.

4 are binding screws in the relatively movable ends of the respective jaws to engage the ring and pivotally connect the same to the jaws at the respective sides of the transverse opening in the ring.

5 is a short lever pivoted to one upwardly

projecting arm of the lower jaw and provided with a counterbalance weight 6 at the movable end thereof. Mounted on this lever near the pivoted end of the same is a ball bearing 7 secured in place by a suitable bolt 8 in the axis thereof. This ball bearing provides for horizontal rotation of its upper member about the axis of the bolt and said member carries the upper jaw 3 rigidly attached thereto. The pivot of the lever 5 permits the lever and upper jaw 3 to move in a vertical plane and the ball bearing 7 permits the upper jaw to swing horizontally.

The upper jaw on its movable end carries a scale beam 10 on which is a scale to indicate the stress in pounds upon the spring as it is deflected by a greater or less extent by adjustment of the weight 11 on the beam. 75 The outer end of this beam traverses a vertically disposed bar 12 and extending from the mid-position upward. On this bar is a scale 13 to indicate in inches and fractions the amount of movement away from each other of the severed ends of the ring and a downwardly extending scale 14 is also on this bar which indicates the inches and fractions of compression or approach of these ends and also indicates the length of the segment to be removed from a similar ring to provide for the stress indicated on the beam 10 when the gap in the ring is closed by compression.

Oppositely extended segments 15 are attached at the mid-position of the bar 13 and extend horizontally in opposite directions therefrom. On these segments are marked scales indicating the amount of torsional movement of the movable end of the ring to the right or left and serve to test the resiliency under torsional stress before producing a permanent distortion or "set" of the ring.

What I claim is:—

1. A ring testing machine, comprising a fixed jaw, a movable jaw, means for pivoting said movable jaw to swing both vertically and horizontally, a beam attached to the movable end of said jaw at one end and horizontal and vertical scales traversed by the other end of said beam to indicate the extent of distortion of the ring both diametrically and laterally.

2. A ring testing machine, comprising a fixed jaw, a lever pivoted to the fixed jaw to swing vertically, a movable jaw carried by the lever pivoted to swing horizontally

thereon and swinging vertically therewith, a scale beam attached to the movable jaw, a weight adjustable on the beam a counter-balance weight on the lever, indicating 5 scales extending both vertically and horizontally traversed by the end of the beam and means for attaching a divided ring to the jaws.

3. A ring testing machine, comprising a 10 fixed semi-circular jaw, a lever pivoted to one end of the same to swing vertically, a ball bearing mounted on the pivoted end of the lever, a counter-balance weight on the lever, a semi-circular movable jaw mounted 15 on the ball bearing and swinging horizontally thereon and also swinging verti-

cally with the lever, a scale beam fixed on the movable end of the last named jaw, a weight on the beam to apply closing stress to the ring, a vertical scale traversed by the 20 end of the beam to indicate opening and closing movement of the ring and a horizontal scale also traversed by the end of the beam to indicate the amount of torsional distortion of the ring.

In testimony whereof I affix my signature in presence of two witnesses.

DONALD J. CAMPBELL.
